UNITED STATES PATENT OFFICE.

THOMAS H. GARLAND, OF CHICAGO, ILLINOIS.

VENTILATOR.

1,071,729.

Specification of Letters Patent. Patented Sept. 2, 1913.

Application filed August 28, 1912. Serial No. 717,445.

To all whom it may concern:

Be it known that I, THOMAS H. GARLAND, a resident of the city of Chicago, in the county of Cook and State of Illinois, have invented certain new and useful Improvements in Ventilators, of which the following is a specification.

My invention relates to ventilators for railway cars and contemplates improved construction and arrangement which will better adapt such ventilators for service on the arch roof type of cars. Ventilators of this class are usually provided with means for controlling the outlet area thereof and an adjustable register mechanism is usually provided. Heretofore the ventilators have been applied to the outside of the arch roof of a car with the entrance to the eduction passageway applied over the outer end of an opening through the car roof, and register mechanism was applied in the inner end of the car roof opening. With such an arrangement the register is in more or less horizontal position and when its vanes are closed a surface is offered for the accumulation of dust, cinders, soot, etc., coming from the exterior of the car and particularly from passing trains, and a slight leakage through the vanes will also draw up lint, dust, etc., into the crevices between the vanes so that as soon as the register is opened the entire accumulation theron falls into the car.

The main object of my invention is therefore to provide such an arrangement that accumulation of dust, soot, etc., will be eliminated and this I accomplish by setting register mechanism in vertical position so that material thrown against the vanes will immediately drop, and I provide a sill board in front of which the material will drop and be prevented from entering the car when the register is opened. A preferable arrangement is to build the register into the ventilator as a structural part thereof, and preferably applied across the mouth of the eduction passageway, a finish grating plate being then applied over the inner end of the outlet opening through the car roof.

Another object is to provide improved arrangement for enabling the register vanes to be readily adjusted from the interior of the car and for this purpose I provide a lever connected with the vanes and extending through the grating and a distance below the car ceiling where it can be readily

engaged and operated to effect the desired adjustment.

The various features of my invention are clearly shown on the accompanying drawings in which—

Figure 1 is a perspective view of the arch roof of a car showing a transverse section thereof and the application thereto of my improved form of ventilator structure; Fig. 2 is an enlarged sectional view from plane 2—2 Fig. 1; Fig. 3 is a sectional view from plane 3—3 Fig. 2, and Fig. 4 is a view like Fig. 3 showing a modified lever arrangement for controlling the register adjustment.

As shown, the ventilator comprises a base 5, and a roof 6, walls 7, 8 and 9 extending between the inner ends of the base and roof to form a compartment 10, wall sections 11 and 12 extending between the outer ends of the base and roof from the outer ends of the walls 8 and 9 and converging toward each other and then running in parallelism at their outer ends, these walls together with the base and roof forming the eduction passageway 13. At the outer sides of the walls 11 and 12, L-shaped walls 14 and 15 span between the base and roof, the outer ends of these walls being parallel with the outer ends of walls 11 and 12 and the inner ends of these L-shaped walls diverging from the inner ends of the walls 11 and 12, there being thus formed at the opposite sides of the walls 11 and 12 the L-shaped cowl passageways 16 and 17 which receive air in a direction longitudinal with respect to the car and which expel the air at right angles thereto, the expelled air deflecting across the outlet of the eduction passageway to create suction effect. When the car is traveling, the advance cowl passageway receives the air and is operative to create eduction effect in the eduction passageway. Within the compartment 10 the base 5 has the opening 18 which in practice registers with the outer end of the opening 19 provided through the arch roof 20 of the car so that the eduction effect in passageway 13 may draw the air out of the car and effect proper ventilation thereof.

Register mechanism is usually associated with the ventilators to control the outlet area thereof but heretofore such registers were placed over the inner end of the car roof opening and when in such position were of course more or less horizontal and

when closed would accumulate dust, dirt, cinders, etc., which would fall into the car as soon as the register was opened. To eliminate such accumulation I dispose the 5 register mechanism within the ventilator and as a structural part thereof and I preferably place it across the inlet end of the eduction passageway 13. As shown, the wall 21 extends across the inlet end of the 10 eduction passageway between the walls thereof and has a rectangular opening 22 across which the register mechanism R is placed. This register mechanism may be of any construction, that shown comprising 15 a plurality of vertical vanes or louvers 23 suitably pivoted and cross connected and having an adjusting stud 24 which when moved laterally will swing the louvers to adjust the outlet area thereof or to entirely 20 close the opening 22. With this arrangement any dust, cinders, etc., which would enter the passageway 13 when the vanes are closed would strike the vanes and would then drop to the bottom of the passageway 13 so that the vanes will always be 25 clean and entrance of dust, cinders, etc., to the interior of the car eliminated. In order to assure that the deflected dust, cinders, etc., will not be blown into the car from the 30 bottom of the passageway 13, the opening terminates at a distance short of the base to leave a sill section 25 in front of which the deflected particles will lodge to be thereby prevented from entering the car when 35 the register is opened. The adjusting stud 24 extends through a slot 26 in this sill section and in order that adjustment of the register can be better accomplished from the interior of the car, various arrangements 40 can be used. As shown in Fig. 3, a Z-shaped lever 27 is pivoted at one bend at any suitable point as, for example, on the bracket 28, one end of the lever having the slot 29 receiving the stud and the other end 45 of the lever extending a distance below the car ceiling and terminating in the eye 30 to be engaged by a suitable device so that upward movement will result in lateral shifting of the stud and corresponding adjustment of the register vanes. In order 50 to present a more finished appearance, a perforated plate 31 may be applied across the inner end of the opening 19 through the car roof and the inner arm of lever 27 55 extended downwardly through one of the openings in this plate. This plate may also serve to support the bracket 28 for the lever as shown in Fig. 3, or, this lever can be pivoted on one of the side walls 32 adjacent 60 the car roof opening 19 as shown in Fig. 1. Another arrangement is shown in Fig. 4 where a vertical rod 33 is journaled in straps 34 on wall 32 and carries at its upper end an arm 35 connected by a link 36 with 65 the stud 24. The lower end of the rod ex-

tends through one of the grille openings and has a wing attachment 37 by means of which the rod may be turned as by means of the ordinary gas valve adjusting rods.

By thus providing register mechanism as 70 a structural part of the ventilator, the arrangement and construction of the device and its application are greatly simplified and owing to the more or less vertical disposition of the register vanes, the accumulation of dust, cinders, etc., is prevented. Where ventilators are applied at the sides 75 of an arch roof, the vanes are diagonally disposed so as to even more readily deflect incoming particles which after such deflection will fall down the inclined base of the ventilator and out of the passageway 13. As soon as the register is opened any accumulated particles will be immediately 80 blown out of the passageway 13 to the exterior of the car by the outflowing air. I do not of course desire to be limited to the exact construction and arrangement shown and described as changes and modifications 85 might be made which would still come within the scope of the invention and I claim the 90 following:

1. In a ventilator for vehicles, the combination of a laterally extending housing having an opening in its base for communicating with the interior of a vehicle to be ventilated, an outlet passageway through said housing extending from said opening, and adjustable register mechanism interposed in said outlet passageway and disposed in vertical position when the ventilator is applied to a vehicle.

2. In a ventilator for vehicles, the combination of a housing having an opening in its base for communicating with the interior of a vehicle, said housing having a horizontal passageway leading to the exterior thereof from said opening, a vertical wall extending across said passageway and having an opening, and a register device applied in 100 the opening of said wall for controlling the outlet area of said passageway, and a sill extending across the lower end of said ventilator for preventing entrance into the vehicle of particles deflected from said register mechanism.

3. In a ventilator for vehicles, the combination of a housing having an inlet opening in its base for communicating with the interior of a vehicle, said housing having a 110 passageway to the exterior thereof from said inlet opening, a register device forming a structural part of the ventilator and positioned therein to control the area of said passageway, and actuating means for said register device extending through said inlet opening for control from the interior of the vehicle.

4. In a ventilator for vehicles, the combination with a housing having a laterally

extending passageway and a vertically extending passageway leading to the interior of the car through the roof thereof, vertically extending louvers arranged in a row 5 and adjustable to close said passageways against each other or to allow connection between said passageways, and lever mechanism connected with said louvers and extending through said vertical passageway 10 into the interior of the car.

5. In a ventilator for vehicles, the combination with a housing having a laterally extending passageway and a vertically extending passageway leading to the interior 15 of the car through the roof thereof, vertically extending louvers arranged in a row

and adjustable to close said passageways against each other or to allow connection between said passageways, a sill in front of the lower ends of said louvers and having 20 a slot, an actuating member extending from said louvers through said slot, and lever mechanism pivoted in said vertical passageway and connecting with said actuating member at one end, the other end of said 25 lever mechanism extending into the car.

In witness whereof, I hereunto subscribe my name, this 26th day of August, 1912.

THOMAS H. GARLAND.
